a corporation of California

Filed Jan. 8, 1960, Ser. No. 1,356
3 Claims. (Cl. 104—88)

The present invention relates to carrier systems, and more particularly to an improved control device for a carrier system.

Normally, a carrier system is utilized to move articles from one place to another along a predetermined path of travel. In such systems, it is often necessary to perform remote operations on the articles as the articles are moved along the path of travel.

Generally, previously available remote control devices for carrier systems have included a switch or photocell located at each station of operation and positioned so as to be selectively actuated by a corresponding lever or light source, as the case may be, disposed on the carrier. Such remote control devices have been relatively expensive and complicated since extensive interconnecting wiring is required, and complicated remote initial adjustment must be made.

An object of the present invention is the provision of an improved control device for a carrier system. Another object of the present invention is the provision of a control device for selectively routing carriers in a carrier system. A further object is the provision of a control device for a conveyor system which selectively controls the branch conveyor to which the carrier is consigned. Still a further object is the provision of a compact control device for a carrier system which is relatively inexpensive and simple to manufacture.

Other objects and advantages of the present invention will become apparent by reference to the following description and accompanying drawing.

In the drawing:

FIGURE 1 is a schematic diagram of a control device showing various features of the present invention, the control device being applied to an overhead conveyor system;

FIGURE 2 is a vertical cross section of the control device; and

FIGURE 3 is a cross sectional view taken generally along line 3—3 of FIGURE 2.

A control device in accordance with the present invention is designed to be used in combination with a carrier system which includes at least one carrier moving along a path of travel. A plurality of stations are located along the path, and means are provided at each station for performing an operation. The control device comprises a strip of magnetizable material, and means for magnetizing a selected area of the strip when the carrier is at a predetermined location along the path. A switch, which is actuated by the magnetized area, is disposed along the strip and is connected so as to actuate the operation-performing means. Means are provided for moving the strip relative to the switch at a speed which is correlated with the speed of the carrier along the path of travel.

To facilitate the understanding of the invention, a brief description of the operation of the carrier system is set forth hereinafter. The carrier system shown in the drawings is a conventional overhead-monorail system, adapted to be used in a slaughtering plant. The sides of meat are loaded on carriers or trolleys 10, one side to a trolley, at a room where the animals are killed and dressed. The loaded trolleys 10 are then stored in sequence on a plurality of storage rails (not shown) until the meat is graded.

When the grading operation begins, each trolley 10 is propelled along a main conveyor track 12 by a main conveyor drive chain 14 past a grading station 16. At the

2

grading station 16, an operator determines the grade of the meat and actuates a consignment switch 18 on a control device 20 to select a branch conveyor 22 where similar grades of meats are to be stored.

When the trolley 10 is adjacent a siding switch 24 leading into the selected branch conveyor 22, the control device 20 causes the siding switch 24 to be switched. The trolley 10 is then propelled by the main conveyor 14 onto the siding switch 24 and thence onto a branch conveyor track 26. As the trolley 10 is moved onto the branch conveyor track 26, the trolley 10 is engaged by a branch conveyor drive chain 28, which is started by the control device 20. When the trolley 10 is clear of the siding switch 24, the siding switch 24 is switched back to its normal position and the branch conveyor drive chain 28 is stopped.

To remove a selected grade of meat from the branch conveyor 22, the operator actuates a push button or switching switch 30 associated with the branch conveyor 22 where the selected grade of meat is stored. The actuation of the push button 30 switches an exit track switch 32 associated with the selected branch conveyor 22 and energizes the branch conveyor drive chain 28. The branch conveyor drive chain 28 propels the trolley 10 onto the exit switch 32 and thence onto an exit or shipping track 34 where an exit or shipping drive chain 36 engages the trolley 10. The exit track switch 32 is maintained in its switched position until the trolley 10 is clear of the switch 32, at which time the switch 32 is moved back to its normal position and the branch conveyor drive chain 28 is stopped.

More particularly, the trolleys 10 are propelled along the main conveyor track 12 by a spaced apart pusher arms 38 carried by the main conveyor drive chain 14.

The branch or storage conveyors 22 are disposed at right angles to the main conveyor track 12. Each branch conveyor 22 includes the track 26 connected at one end to the main conveyor track 12 by the siding switch 24 which is operated by a solenoid 40. A plurality of spaced apart pusher arms 42, which are carried by the branch conveyor chain 28, are disposed so as to engage the trolleys 10 as the trolleys are propelled onto the branch conveyor track 26. The chain 28 is driven by a motor 44 suitably connected thereto.

The other ends of the branch conveyor tracks 26 are connected to the shipping or exit conveyor track 34 by the exit switch 32 which is operated by a solenoid 46. A plurality of spaced apart pusher arms 48 are carried by the exit conveyor drive chain 36, the pusher arms 48 being adapted to engage the trolleys 10 as they are propelled onto the exit conveyor track 24.

As shown in FIGURES 2 and 3, the control device 20 includes a plurality of strips or rings 50 of a suitable magnetizable material, such as magnetizable iron, disposed in spaced apart relationship on a drum 52 of a non-magnetizable material, such as aluminum. One ring 50 is associated with each branch conveyor 22. The drum 52 is fixedly attached to a shaft 54 which is journaled in bearings 56 disposed in the side walls 58 of a housing 60.

The shaft 54 and the drum 52 are rotated by a synchro motor 62, the speed of the motor 62 being controlled by a synchro generator 64 connected to the main conveyor drive chain 14. In this way, the peripheral speed of the rings 50 is in direct proportion to the speed of the trolley 10. The circumference of the rings 50 is made such that before the rings 50 make one complete revolution, one of the trolleys 10 can be propelled from the grading station 16 to a position past the branch conveyor 22 last in line.

Since the periphery of the rings 50 is moving at a speed which is in direct proportion to the speed of the trolley 10, the distance between two points on the periphery of the

rings 50 is proportional to the distance travelled by the trolley 10. Accordingly, the siding switch 24 may be operated at the proper time to shunt the trolley 10 onto the selected branch conveyor track 26 by magnetizing a selected area of the ring 50 associated with the branch conveyor 22, when the trolley 10 is at a predetermined location on the main conveyor track, and employing the magnetized area to operate a magnetic operated switch 66 positioned along the rings 50.

In the illustrated embodiment, a selected area of the ring 50 is magnetized by an electromagnet 68, suitably supported by the housing 69 so as to be adjacent the periphery of the ring 50. The electromagnet 68 is actuated by manually closing the consignment switch 18, the switch 18 being connected in series with the electromagnet 68 and a power source which, for purposes of illustration, is shown as a battery 70.

So that the electromagnet 68 is actuated when the trolley 10 is at a predetermined location on the main conveyor track 12, a main control switch 72 is provided which is actuated by the trolley 10 as it moves along the main conveyor track 12. The main control switch 72 is connected in series with the power source 70 and the parallel connected consignment switches 18.

The solenoid 40 of the associated siding switch 24 is actuated just before the trolley 10 reaches the associated siding switch 24 by the magnetized area of the ring 50 actuating the magnetic operated switch 66 which is suitably supported by the housing adjacent the periphery of the ring 50. The operating arm of the illustrated magnetic operated switch 66 is provided with a roller 74 of a soft magnetic material which is attracted by the magnetized area on the ring 50. The magnetic operated switch 66 is disposed at a distance from the electromagnet 68 which is in the same proportion to the distance from the main control switch 72 to siding switch 24 as the speed of the ring 50 is to the speed of the trolley 10.

The magnetic operated switch 66 is connected in series with the power source 70 and a pilot relay 76. For purposes of clarity, a portion of the conductor extending between the switch 66 and the power source 70 is not shown in the drawing. The two ends of the conductor are each indicated by an arrow designated by "X." This scheme is followed hereinafter for connections between the power source and the parts of the circuit. It should be understood that all X's are connected together. When the pilot relay 76 is energized by the closing of the magnetic operated switch 66, a normally open contact 78, which is operated by the relay 76, is closed. The contact 78 is connected in series with the siding switch solenoid 40 and the power source 70, and thus the siding switch 24 is transferred by the closing of the contact 78.

Since the siding switch 24 should be maintained in a transferred condition until the trolley 10 has been propelled onto the branch conveyor track 26, a holding circuit is provided for the siding switch solenoid 40. The holding circuit includes a holding relay 80 which is connected in parallel with the siding switch solenoid 40. A normally open contact 82 of the holding relay 80 is connected in series with a normally closed contact 84 of a timing relay 86, and the series combination is connected in parallel with the pilot relay contact 78 to thereby by-pass the contact 78.

As the trolley 10 is propelled into the branch conveyor 22, it is received by the pusher arms 42 carried by the branch conveyor chain 28. The drive motor 44 of the branch conveyor chain 28 is energized by the closing of a normally open contact 88 of the holding relay 80, the contact 88 being connected between the power source 70 and the drive motor 44.

As the trolley 10 is propelled along the branch conveyor track 26, it closes a normally open timing switch 90 which is connected in series with the power source 70 and the timing relay 86. The timing relay 86 becomes energized and opens the normally closed contact 84 thereof. Accordingly, the current is interrupted to the siding

75 solenoid 40 and the drive motor 44 of the branch conveyor 22, and thus the branch conveyor chain 28 is stopped and the siding switch 24 is returned to its normal position by a spring (not shown).

5 The magnetized area of the ring 50 is erased by a permanent magnet 91 which is suitably supported by the housing 69 adjacent the periphery of the ring 50 immediately before the electromagnet 68. It should be understood that more than one magnetized area may 10 appear on the ring 50 and it is not necessary to wait for the magnetized area to be erased before magnetizing a second area of the ring 50. In addition, more than one ring 50 may be magnetized during one revolution of the ring 50.

15 The sorting process may be continued until the branch conveyor track 26 are filled with trolleys 10, or may be stopped at any time prior to this.

When it is desired to remove trolleys 10 from the branch conveyors 22, the shipping conveyor drive chain 20 36 is started. Then, the normally open shipping switch 30, which is associated with the selected branch conveyor 22 from which the trolley 10 is to be removed, is closed. As shown in the drawings, the closing of the shipping switch 30 completes a circuit from the power 25 source to the solenoid 46 which, upon energization, operates the exit switch 32. The shipping switch 30 also energizes an auxiliary relay 92 which is connected in parallel with the exit switch solenoid 46. A normally open contact 94 of the auxiliary relay 92 is connected 30 in series with a normally closed contact 96 of an output relay 98, and the series combination is connected in parallel with the shipping switch 30. In this way, the solenoid 46 is kept energized until one of the trolleys 10 35 is propelled from the branch conveyor track 26 onto the shipping conveyor track 34.

A normally open contact 100 of the auxiliary relay 92 is connected in parallel with the normally open contact 38 of the holding relay 80 so that the branch conveyor drive motor 44 is energized when the shipping switch 30 40 is closed. Accordingly, when the shipping switch 30 is closed, the branch conveyor 22 propels the trolley 10 out of the branch conveyor 22 onto the shipping conveyor track 34.

As the trolley 10 is propelled onto the shipping conveyor track 34, it operates an output switch 102. When the output switch 102 closes, it energizes the output relay 98, which is connected in series therewith. The energization of the output relay 98 causes its associated 50 normally closed contact 96 to open, thereby deenergizing the exit switch solenoid 46 and the branch line conveyor drive motor 44.

In operation, the loaded trolley is propelled past an operator who determines to which branch conveyor 22 the trolley 10 is to be consigned. The operator closes 55 the consignment switch 18 associated with the selected branch conveyor 22 and, when the main control switch 72 is closed by the trolley 10, a selected area of the ring 50, which is associated with the selected branch conveyor 22, is magnetized. The trolley 10 is propelled along the main conveyor track 12 until it reaches a position just before the selected branch conveyor 22. The magnetized area on the associated ring 50 then actuates the magnetic operated switch 66 which, in turn, actuates the pilot relay 76. The closing of the normally open contact 78 of the pilot relay 76 energizes the solenoid 40, which operates the siding switch 24, and a holding relay 86. The energization of the holding relay 80 and the closing of its contacts 82 and 88 causes the branch conveyor drive motor 44 to be activated and keeps the solenoid 40 energized until the trolley 10 actuates the timing switch 90. The closing of the timing switch 90 65 energizes the timing relay 86, and the contact 84 of the timing relay 86, in turn, deenergizes the solenoid 40 and

the branch conveyor drive motor 44. Consequently, the siding switch 24 returns to its normal position.

It should be apparent from the above that a control device constructed in accordance with the invention provides a compact, readily adjustable, and easily operated control for a conveyor system. Moreover, it should be understood that the control device may be used with conveyors other than the conveyor illustrated in the drawing. For example, the control device may be used to stop a conveyor as the carrier reaches certain remote stations. Also, the control device may be employed to control the operation of equipment, such as paint sprayers, driers, etc.

Various modifications may be made in the above described control device, without deviating from the spirit or scope of this invention. Various features of the invention are set forth in the accompanying claims.

We claim:

1. A control device for a carrier system including a plurality of carriers moving along a path of travel, a plurality of stations located along the path, and means at each station for performing an operation, said control device comprising a plurality of coextensive, mechanically interconnected endless strips of magnetizable material, one of said strips being provided for each station, means associated with each strip for perpendicularly magnetizing a selected area of the outer surface of its strip; means for selectively energizing said magnetizing means when one of the carriers is at a predetermined location on said path, a switch associated with each endless strip for actuating the operation-performing means of the station for which said strip is provided, each switch including an operating arm, and a roller of magnetic material on said arm, said roller being disposed adjacent the outer surface of its strip so as to be attracted by the magnetic field of said selected area to thereby move said arm and actuate said switch, means for moving said strips relative to said switches and to said energizing means at a speed which is in the same proportion to the speed of the carrier along the path of travel as the distance from the magnetizing means on one strip to the roller on the same strip is to the distance from said predetermined location to a location on said path immediately before the station for which said strip is provided, and means disposed along each endless strip after said magnetic operated switch for erasing the magnetized area.

2. A control device for a carrier system including a plurality of carriers moving along a path of travel, a plurality of stations located along the path, and means at each station for performing an operation, said control device comprising a plurality of rotatably mounted, coaxial rings of magnetizable material, one of said rings being provided for each station, means associated with each ring for perpendicularly magnetizing a selected area of its ring, means for selectively energizing said magnetizing means when one of the carriers is at a predetermined location on said path, a switch associated with each ring for actuating the operation-performing means of the

station for which its ring is provided, each switch including an operating arm, and a roller of magnetic material connected to said arm so that movement of the roller effects operation of said switch, said roller being disposed along and adjacent the periphery of its ring so as to be moved by the magnetic field of the selected area, means for rotating said rings relative to said switches and said energizing means at a speed which is in the same proportion to the speed of the carrier along the path of travel as the distance from the magnetizing means on one ring to the roller on the same ring is to the distance from said predetermined location to a location on said path immediately before the station for which said ring is provided, and means disposed along each ring after said switch for erasing the magnetized area.

3. A control device for a carrier system including a plurality of carriers moving along a path of travel, a plurality of stations located along the path, means at each station for performing an operation, said control device comprising a rotatably mounted drum having a plurality of rings of magnetizable material thereon, one of said rings being provided for each station, an electromagnet associated with each ring and disposed adjacent said ring for perpendicularly magnetizing a selected area of its ring, a power source, a switch actuated by said carrier when said carrier is at a predetermined location on the path, a selector switch associated with each ring connected in series with said power source and said electromagnet for selectively energizing said electromagnet, a switch associated with each ring for actuating the operation performing means for which its ring is provided, said switch being disposed along the periphery of said ring and having an operating arm, and a roller of magnetic material carried by said arm and disposed adjacent the periphery of its ring, means for rotating said drum at a speed which is in the same proportion to the speed of the carrier along the path of travel as the distance from the electromagnet to the magnetic roller is to the distance from said predetermined location to a location on said path immediately before the associated station, and means disposed along said ring after said magnetic operated switch for erasing the magnetized area.
